UNITED STATES PATENT OFFICE

2,528,813

METHOD FOR CREATING POWER

Ransom Y. Bovee, Van Nuys, Calif.

Original application April 23, 1943, Serial No. 484,201, now Patent No. 2,421,868, dated June 10, 1947. Divided and this application January 13, 1947, Serial No. 721,713

3 Claims. (Cl. 123—33)

1

This application is a division of application Serial Number 484,201, filed April 23, 1943, for invention entitled "Engine" which matured into Patent Number 2,421,868 and which bears an issue date of June 10, 1947.

This invention relates to an internal combustion engine employing but a single means to control the ingress of fuel and air into a plurality of abutting cylinders and/or power units, and also for controlling the discharge of burned gases from the power units. As regards the cylinders of one possible form of the engine of this invention, the engine may have two similar or complementary-like parts with the open ends of their respective gas chambers in substantially the same plane, the two parts being separated only by a single valve plate that is common to all the cylinders. The disc shaped plate valve can operate between two duplex opposed barrel engines and thus is a true monovalve for both engine parts.

By the duplex and opposing features of the two engine parts, ignition and complete combustion of the fuel gases is accomplished in a simple and economical manner, the engine operates in perfect balance, and, therefore, is vibrationless; it is substantially noiseless, the drag is reduced to a very low minimum, fire hazard greatly lessened, weight and costs are very low, and mass production made possible for this type of engine because of its simplicity and uniformity of like parts.

Although the engine of this invention may be arranged for electrical firing of the fuel, it is preferable to construct the engine for high gas compression firing in a manner somewhat similar to the Diesel Engine principles.

Any number of power delivery cylinders and gas or air compression cylinders may be used in the engine of this invention. A gas-firing or igniter cylinder is paired with and connected to each power delivery cylinder for transmittal of hot high pressure gases to its respective power delivery cylinder via a passage where a predetermined amount of liquid fuel is entrained and diffused in the hot firing gases. In the power delivery cylinders, the mixed explosive gas expands and disposes of substantially all its energy for substantially the full length of the strokes or displacement of the power delivery pistons.

Instead of the usual crank shaft, the power of the engine of this invention may be transmitted from the power delivery cylinders to a crankless straight main drive shaft through a series of connecting rods that work in sliding manner along the edges of a pair of slant rotors or crank-

2

discs, the discs having their hubs firmly fixed to the main drive shaft. This arrangement permits a large number of long power thrusts to the main drive shaft in perfect balance and assures a long dependable service for all working parts.

Each engine half or section may have any number of paired power delivery and gas compression cylinders, which when abutted with the like cylinders of the other half of the engine form 10 a unitary power delivery engine with a single in between rotary valve, all the cylinders and valve having their respective working parts centered about a single crankless drive shaft. The engine of this invention may be a truly duplex power 15 delivery mechanism having multiple cylinder units opposed to one another. The arrangement of the cylinders and valve plate being such that carbon accumulating areas are eliminated, the pistons of the cylinders may substantially abut 20 against the sides of the single valve plate which makes possible complete scavenging of burnt gases and full power strokes, perfect balance of power thrusts, and reduce much friction and wear.

25 Some of the objects of this invention are as follows:

1. To present a method which causes a duplex engine to be balanced on opposite sides of a single rotary control valve arrangement, the 30 method being very efficient in operation, the engine simple in construction, and economical to manufacture.

2. To provide a super-engine method capable of burning unrefined fuels and having means of 35 transforming crude petroleum or liquid base fuels into instantaneous combustive action by inherent engine block means without the aid of carburetors, preheaters, atomizers or ignition devices.

3. To provide a method capable of expanding 40 the products of combustion in the development of power to the maximum extent of their useful power value.

4. To provide an internal combustion engine which operates under a method in which the expansive effort of the explosions is consumed in 45 the power thrust, and substantially to a point where the exhaust pressure when released is substantially noiseless, heatless, flameless and pressureless.

5. To provide an internal combustion engine method in which steps mix air and fuel after top dead center of the working pistons, which prevents and obviates explosive effort from back-thrusting contra to the running direction of the 55 engine which consumes power, causes for heat-

ing on the upward stroke of the piston heads, cylinders and compression spaces, unnecessary thermal heat losses, and unconvertable power loss in detrimental heat dissipation.

6. To provide a method wherein internal combustion engines obviate the necessity of advance ignition and advance fuel introduction, which prevents and obviates pre-ignition, detonation, and two-way exposure to flame of the explosion ends of the cylinders.

7. To provide an internal combustion engine method including automatic means of compression ignition inherent to the means and method of pre-compression of air, and fuel introduction thereinto and then transference to an independent cylinder for expansion and delivery of power.

8. To provide an internal combustion engine method by which pre-compression of air to fuel-combustion temperature enables the fuel to be introduced into the air-stream while in transition from one cylinder to another, producing cyclonic turbulence and fuel atomization to a point of near-infinity, rendering the fuel and the air into a homogenized flaming gas, thereby insuring complete combustion, and combustion after top dead center on the outward working stroke of the power delivery piston.

9. To provide a method for monovalve engines whereby four-stroke functions occur in two-strokes without blowers or scavenging devices, whereby a single valve means admits air induction, air-compression, compressed air transferance, fuel introduction in a manner to cause 100% fuel diffusion, atomization to near-infinity, inflammation and combustion from air pre-compressed high temperatures, and a power stroke extending from the top of the power cylinder to the bottom before exhausting the products of combustion, all in two cycles of operation, utilizing up to 75 degrees more thrust than prevails in common practice.

10. To provide a monovalve engine method which enables compound expansion of the explosions and expanding gases to nearly their atmospheric pressure limits before being exhausted, in which the explosions are expanded to nearly two and two-thirds greater displacement before being exhausted than occurs in prevailing engines.

11. To provide a method where a relatively small displacement can be expanded into a larger displacement to obtain a full delivery of expansive explosive effort in working piston thrust before exhaust.

Other objects, advantages and features of my invention will appear from the accompanying drawings, the subjoined detailed description, the preamble of these specifications and the appended claims.

Applicant is about to illustrate and describe one of the forms in which his methods can be practiced, and submits a detailed description. It is to be understood that the drawings and description thereof are not to limit the invention in any sense whatsoever, except as limited by the appended claims.

In the drawings:

Figure 1 is a side elevational view of a barrel type engine capable of practicing my method, parts being broken away to show some of the internal parts;

Figure 2 is an enlarged sectional view of a portion thereof;

Figure 3 is a sectional view taken substantially along the line 3—3 of Fig. 2.

The engine illustrated in the drawing and

which comes within the purview of this invention, has a pair of abutting outer cylindrical casings or shells 1 and 1', the far ends of which are flanged to provide annular surfaces to accommodate the end disc-like sealing plates 2 and 3. The end plates are removable and may be held tightly against the ends of the shell by any suitable means such as bolts and the like. Each end plate is provided with a bearing to centrally and 10 rotatably support a hollow shaft 4 with its ends open as shown. The two cylindrical shells at their abutting ends have the annular flanges 5 and 6 which are bolted together after first placing between them an annular spacer ring 7 which provides a shallow annular or ring-like area 8 to accommodate a rotatable mono-valve or rotary disc-shaped valve plate 9. This valve plate divides the engine and provides the two engine chambers 10 and 11. Each engine portion 1 and 1' are provided with water channels 11' and 11'' respectively, which surround their respective cylinders to be later explained.

The valve plate has a central circular opening which is journaled onto the outer surface of the collar of a bevelled gear 12, the bevelled gear being journaled to the other surface of the main drive shaft 4. To a central portion of the valve plate surrounding the opening thereof is fixed the flange of a ring gear 13 which meshes with means for slowly turning it and which is explained in detail in the Patent No. 2,421,868 referred to above.

The disc-shaped plate 9 is a rotary engine head or partition between a plurality of power delivery cylinders in chambers 10 and 11 and also between a plurality of gas heating or air compressor cylinders in the chambers 10 and 11. All the power delivery cylinders in chamber 10 are indicated by the numeral 14, and the similar abutting power delivery cylinders of chamber 11 are indicated by 15. The compressor cylinders in chamber 10 are indicated by 16, and the similar abutting compressor cylinders of chamber 11 are indicated by 17. The power delivery and compressor cylinders all have the usual internal combustion engine type pistons 18 and 19 respectively, all of which are provided with a threaded bore into each of which is threaded an end of a rigid piston rod 20.

Attached to the outer ends of the piston rods 20 are the cross heads or slide connector units 21 coupled to their respective piston rods by a threaded and tapered offset extension 22 which is split axially thereof so that when the nut 23 is screwed thereon, the extension is squeezed to a smaller compass to snugly grasp the piston rod. The very end of the piston rod is screwed to the inner portion of the extension at 24 in order to be rigidly and firmly held thereto. Means is combined with each connector unit to slide smoothly around the outer margin of a slant-rim rotor or wobble type crank which vacillates when the drive shaft 4 is rotated; one of these wobble cranks is designated 25 and the other 26.

The rotatable shiftable valve plate 9 has six evenly spaced transfer ports or openings 27 which make connections between the neighboring compressor cylinders and power delivery cylinders, 16—17 and 14—15 respectively. As explained in the patent, means are provided for admitting air to the compressor cylinders and means provided for periodically exhausting the burned gases from the power cylinders. The valve plate is uniformly shifted by the drive shaft so as to make the properly timed connections for admitting the fuel mixture to the power cylinders and

for exhausting the burnt gases. A rail or tube means is used for conducting high pressure fuel to the various nozzle communication passages 29. The passage 29 opens to the valve chamber 30 wherein is the fuel control valve 31 which injects the fuel into the passage 29.

Each passage 29 leads to a fuel jet or injection nozzle or the like 32 which sprays the fuel into the communicating transfer slot or port 27 of the disc-like valve plate 9; and from this slot or port, the fuel oil along with the hot firing gas or air from the compressor cylinders are forced by their own pressure into the power delivery cylinders. Full and complete expansion occurs in each power delivery cylinder until the end of the strokes of the pistons.

Operation and methods involved

The fuel passes through the admission valve 31, passages 29 and through injection jets 32 into the monovalve high compression transfer ports 27 which in progressive sequence admit fuel into the compression heated air streams being forced through the transfer ports by the air compression cylinders 16 and 17, and thence into the explosion cylinders or power delivery cylinders 14 and 15. The pre-compression temperatures from compressor cylinders 16 and 17 exceed 1000 degrees of temperature, and approach a mile a second speed in transit from cylinders 16 and 17 through transfer ports 44 and into explosion cylinders 14 and 15; thus, exploding the homogenized fuel and air mixture against pistons 19 which, and their cylinders 14-15, are sealed by valve 9 after charging with the explosive mixture from the ports 44. Expansion from the explosions drives pistons 19 in cylinders 14 and 15 outward from each other resulting in power thrust against ball socketed thrust slippers which ride the marginal surfaces, front and rear, of wobble crank discs 25 and 26 producing rotation thereof and the driveshaft 4.

The modus of functional operation permitting the adaptation of the single monovalve to this type of an engine is based upon the combining of four-cycle functions in two-cycles of functional operation, adaptation of balanced or equal opposition of opposing forces against the monovalve, the creating of a four cylinder coactional opposed group or set of cylinders which through duplex-opposition astride a cylinder-head valve, the cylinders being set in large then small tandem fashion so that each engine side has five sets of cylinders which are opposed by a like cylinder arrangement in the other side of the engine, thus making possible by two-stroke operation the adaptation of a common exhaust and intake port in the valve to serve both exhaust and intake functions from one cylinder to the other in a revolution of the engine and the piston movement. Also permitting the adaptation of a single air transfer port between the opposition pairs of large and small cylinders to act in timed sequence to commence the transfer of air from the two opposed air compressor cylinders 16 and 17 respectively to the two larger explosion cylinders 14 and 15 after the end dead center meeting of the explosion cylinder pistons 19 on either side of the valve 9, and then cutting off the communication therebetween when the smaller pistons 18 meet as their reversal movement begins. Thus, a four-cylinder opposed co-actional set with an accompanying valve is created, within a limited arc of movement of both the valve and the segment of the arc occupied by the four-cylinder set or group as it relates to the circle

around which the cylinders are set in opposition. There being room for both valve movement and high compression ratios adequate for compression ignition in a circle for a maximum of five sets of cylinders, each set from one to five being a complete engine in itself not dependent upon any of the other four sets to function. Each set is preferably segmented into 72 degrees of the circle of 360 degrees, which enables a lag or drag action of the pistons 18 of 31½ degrees to approximately 33½ degrees after the explosion pistons 19 have reached top-dead-center which respective actions provide the necessary compression ratio in the compression cylinders 16 and 17 to automatically explode or burn the transitionally injected fuel and air driven into and between the out-acting power-pistons 19. Thus, the valve action 9 becomes in ratio of speed and revolutions, one-sixth that of the drive shaft 4, having six 60 degree spaced port sets comprising a transfer port or passage, 27, an intake-exhaust passage and a cam groove and cam or plunger depressor to each of the valve port-sets. To produce a compression ignition ratio, again the strokes of the pistons should be equal to twice the diameter of the bore or more, and the motion of piston reciprocation uniform and harmonic, thus the approximately two and one-third times the bore length of stroke or thereabouts is again an essential factor in the operation of the monovalve engine principle in obtaining compression ignition pressures, and transferring them in relative movement to advance-set combustion cylinders. By the foregoing arrangement and principle of operation, the air volume entering through inlet ports and passing through valve ports, and into compression cylinders 16-17 is compressed therein and transferred through valve port 27 into explosion cylinders 14-15 of each respective set; the fuel being injected through the jet of each respective set into the valve transfer port 27, the shearing off of the fuel at jet 32 into the air-stream under 1000 degrees of compression heat, and at nearly a mile a second velocity combined with cyclonic turbulence as the fuel and air split against the transfer-port end to equally fill the retreating displacement of the outgoing power pistons 19. The combustion takes place from the fuel transformation taking place sheared to near infinity off the fuel jets and blasted into the power cylinders in a state of flame. Thus, there is no usual process of flame propagation, as instantaneous transformation of fuel under high temperatures produces combustion but little beyond the period of transfer and injection, expanding in the greater displacement explosion cylinder to more than one and six-tenths the volume of its intake displacement instead of six-tenths its intake volume as applies in present engines before the exhaust valve opens. Thus, the duplex-opposed four-cylinder monovalve set-unit of co-acting operation enables compound-expansion of the combustion in the power delivery cylinders 14-15 to nearly atmospheric pressure before being exhausted out through suitable ports. The power pistons 19 meeting against the valve 9 in exhausting the burned residual gases, provides full scavenging, with a substantially noiseless exhaust. The introduction of fuel into the transferring air-stream, obviates mixing devices, atomizers, carburetors, or preheaters, eliminates compression spaces, ignition devices, blowers or scavenging devices, prevents pre-ignition, back-thrust or the possibility of detonation, and enables any type of fuel to be employed from crude oil to volatile

ether without change or adjustment of the throttle valve or change of fuel pressure regulator valve in the fuel pump. The intake air volume at low altitudes remaining constant, the throttle valve, by increasing or lessening the volume of fuel admitted to the fuel ring 28, governs the speed and power of the engine, the engine being stopped by closing the fuel throttle. The fuel pump volume capacity exceeding the maximum fuel requirements, the excess fuel is by-passed by fuel pressure regulator valve into a reduced pressure take off chamber leading to the starter pressure tank, the reduced pressure for starter tank charging being controlled by starter pressure regulator valve and a tank charging outlet, the overflow being by-passed into a passage leading back into the fuel pump intake.

Having thus described one way in which the methods of my invention can be practiced, what is claimed as new and desired to be secured by Letters Patent is:

1. The method of providing power thrusts in opposite directions with respect to a common separator; the step of creating a fuel burning gas at fuel ignition temperature and passing it into

intimate crosswise relationship with a stream of fuel, and then passing the mixed fuel and gas into a pair of chambers where the mixed fuel and gas is expanded in opposite directions to deliver power.

2. The method recited in claim 1 wherein the fuel stream is atomized as it contacts the high temperated gas.

3. The method recited in claim 1 wherein the fuel stream is atomized and swept away by the high temperated gas at extremely high velocity.

RANSOM Y. BOVEE.
